UNITED STATES PATENT OFFICE.

WILLIAM E. WINE, OF TOLEDO, OHIO.

VENTILATED FREIGHT CAR.

Application filed November 9, 1925, Serial No. 67,820.

My invention relates to new and useful improvements in the ventilation of box cars, and has for an object to arrange the ventilators to procure a more perfect ventilation than has heretofore been possible in freight cars, and to also so support some of the ventilators adjacent the side doors so that the one wooden support or door post will act as a stop for the door and also form the means to which the ventilators are attached.

The present application is similar in some respects to my copending application, filed March 20, 1925, bearing Serial No. 16,985, and one filed of even date herewith, bearing Serial Number 67,821.

As pointed out in the previous application, it is desirable to have more than two ventilators in a car, one at each end, which is the usual practice, but there are certain disadvantages in adding ventilators to the car doors as they naturally increase the weight of the door. I have found that if additional ventilators are placed adjacent one side of the doorway, and in staggered relation in opposite sides of the car, the ventilation is greatly increased.

I have also found that if ventilators are provided in staggered relation on the opposite sides of the car, and adjacent the door ways, with additional ventilators at the sides of the car, but near its ends, the ventilation is still further increased, and the present application has to do with this arrangement and the various features to be hereinafter pointed out.

With these and other objects in view, the invention consists in certain new and novel arrangements and combination of parts as will be hereinafter more fully described and pointed out in the claims.

Referring now to the drawings, showing a preferred embodiment of the invention,

Fig. 1 is a fragmentary side elevation of a freight car having the ventilators arranged adjacent the door openings and in staggered relation.

Fig. 2 is a horizontal sectional view showing how the door post acts as a support for one edge of the ventilators, adjacent thereto, and also as a stop in closing the car door.

Fig. 3 is a side elevation on a reduced scale showing the ventilators adjacent the door opening and a ventilator appearing near the upper corner of one end of the car, and another ventilator on the opposite side at the other end of the car, and

Fig. 4 is a horizontal sectional view taken on line 4—4 of Fig. 3, showing the location of the several ventilators.

Referring now to the drawings more in detail, and for the present to Figs. 3 and 4, I have shown a freight car 1 having the door openings 2 and 3, and their respective doors 4 and 5. Adjacent the opening 3 are the two ventilators 6 and 7, while adjacent the opening 2 are the two ventilators 8 and 9, these ventilators appearing in staggered relation, similar to the position of the ventilators in my copending application, Serial No. 16,985.

In the present invention, instead of providing ventilators at the opposite ends of the car, as shown in my copending application, I position a ventilator 10 in the upper left hand corner on the side of the car, while at the other side of the car and near the right hand corner, I position a ventilator 11.

In the common practice of building freight cars, a ladder is provided on the sides of the car near its opposite ends, and I have shown one at 12, and the other at 13 (see Fig. 4).

I have found this arrangement preferable for the two end ventilators, as in each instance, the ventilator is across the car from the ladder, instead of directly behind the same, where it might be possible for a trainman to catch his foot in the ventilator and thereby injure himself, or cause him to fall while mounting or dismounting the car.

I have also found that it is preferable to mount the ventilators 10 and 11 in the sides of the car near the ends thereof, rather than in the ends themselves, as this permits of a cross circulation of air which is otherwise not possible.

In Fig. 4, I have shown by arrows, a cross circulation of air for the car, and it will be seen that the car is thus completely ventilated, not merely from one end to its other through the center, which is often the case when the ventilators are at opposite ends of the car, but the entire car will have drafts and cross drafts throughout its width and length.

The upper ventilators also permit the stale hot air to escape from the upper portion of the car, while the lower ventilators of the car permit the ingress of the fresh cool air. Any form of ventilators might be used, but preferably the Wine type, of which I am the patentee.

Referring now for the moment to Figs. 1 and 2; (Fig. 1 being a slightly enlarged view) there will be noticed the door post 14, adjacent the door opening 3, and as may be seen in Fig. 2, a standard 15 is shown as strengthening the post 14 through both of which passes a bolt 16 which is adapted to be secured within the side frame 17 of the ventilator. It will thus be seen that this door-post 14 functions as a door post, a door stop and a support for the two ventilators. The door 5 when closed will abut the projection of the doorpost 14, thus doing away with an additional door stop, and the post also forms a means for supporting the adjacent edges or sides of the two ventilators 6 and 7. As may also be seen in Fig. 2, and in dotted lines in Fig. 1, an upright or post 18 is placed between the sheathing or car, and a bolt 19 is shown tying this side of the ventilator frame to the post.

Although Fig. 2 shows but one ventilator, it will be understood that both ventilators are secured between the two posts in a similar manner.

The door post on the opposite side of the car from that shown in Fig. 2 is identical and the arrangement of the several posts is the same, but in this instance, the combined door post and stop 20 (Fig. 4) is diagonal to the previously mentioned one, 14, the door, of course, moving from the opposite direction.

It will be appreciated from above that the installing of the ventilators in the car is greatly simplified, that the labor is lessened, and furthermore, the door posts acting in the manner above outlined simplifies the construction and deducts from the cost of the installation.

It will also be seen that the arrangement of the several ventilators outlined make it possible to thoroughly ventilate the car from end to end which is necessary for the cars that are used especially in the south-eastern territory.

I am aware that it is old in the art, such as in Wänds, 370,667 of September 1887, to provide ventilators in the upper corners of a car, but it will be appreciated that in this instance, no means is provided for the ingress of fresh air, and unless the staggered

ventilators as shown in applicant's device are provided, the scientific arrangement of ventilation is not produced.

I am also aware that it is old in the art to provide slats in a poultry car, or in a fruit or produce railway car. However, the present application has to do with the staggered relation of the ventilators so as to produce the many cross currents as heretofore described, and to also provide a means for reducing the installation to a minimum, and at the same time performing the several functions with the one instrumentality.

Many slight changes might be made without in any way departing from the spirit and scope of the invention.

Having thus described the invention, what I claim as new and desire to secure by Letters Patent is:—

1. A freight car having the usual closed ends and sides and the usual ladders arranged on the sides of the car near the opposite ends and diagonally across from each other, the said car provided with door openings in its sides and door posts forming respectively one side of each of said openings, said door posts extending outwardly to form door stops, ventilators secured to said door posts, and means for supporting the remaining sides of the respective ventilators, and further ventilators located near the ends of the car and respectively directly across from the ladders.

2. A freight car having the usual closed ends and sides and the usual ladders arranged on the sides of the car near the opposite ends and diagonally across from each other, the said car provided with door openings in its sides and door posts forming respectively one side of each of said openings, said door posts extending outwardly to form door stops, ventilators secured to said door posts and on the respective opposite sides from the direction of opening movement of said respective doors, means for supporting the remaining sides of the respective ventilators, and further ventilators located near the ends of the car and respectively directly across from the ladders.

In testimony whereof I affix my signature.

WILLIAM E. WINE
